UNITED STATES PATENT OFFICE.

BRUNO KNIFFLER, OF CLEVELAND, OHIO.

CENTRIFUGAL REEL.

SPECIFICATION forming part of Letters Patent No. 326,509, dated September 15, 1885.

Application filed June 25, 1885. (No model.)

To all whom it may concern:

Be it known that I, BRUNO KNIFFLER, of Cleveland, in the county of Cuyahoga and State of Ohio, have invented new and useful 5 Improvements in Centrifugal Reels; and I do hereby declare that the following is a full, clear, and exact description thereof, reference being had to the accompanying drawings, which form a part of this specification.

10 This invention relates to certain new and useful improvements in the class of flour-dressing machines usually known as "flour-bolts;" and the invention consists in the construction, arrangement, and combination of various 15 parts, all as more fully hereinafter described.

In the drawings which accompany this specification, Figure 1 is a perspective view of my improved machine, showing the rear end thereof. Fig. 2 is a perspective view of the front 20 end. Fig. 3 is a horizontal section on the axis of the shaft of the bolting-reel. Fig. 4 is a vertical central cross-section. Fig. 5 is a horizontal section on line $y-y$ in Fig. 4. Fig. 6 is a detached view of the driving-gear and clutch. 25 Fig. 7 is a detached perspective of front and rear of the head which forms the rear end of the bolting-reel. Fig. 8 is a detail on an enlarged scale.

A is the main shaft, running horizontally 30 through the center of the machine, and projecting beyond both ends of the same; and B is the drive-pulley, secured to either end of the shaft. This shaft is journaled in suitable boxes, a b, supported by the frame of the machine, and has secured to it the beater-frame C, which is of known construction and operation.

D and E are the heads of the reel-cylinder; and F is the bolting-cloth, secured to the periphery of these heads and supported between 40 them, so as to form the usual bolting-reel.

In the drawings the bolting-cloth is supported between the heads in the following manner: A cylindrical cage is formed between the 45 two heads by a series of stays, h, to which, at suitable distances apart, the clamps i are secured, so as to form radial supports for the hoops j, which are secured thereto. The bolting-cloth is made of the proper cylindrical shape to fit over the cage, and is secured at its ends in any suitable manner to the heads and

also to the loose ring k, by means of which and the bolts l it is drawn tight in the usual manner.

The front head, D, is provided with a hollow hub, c, which is journaled in the box d, and the rear head, E, has a hollow hub, e, which is sleeved upon the shaft A and journaled in a box, f.

G is the spout-box, to which the lower end 60 of the feed-spout is secured. It communicates with the hollow hub c of the head D, and a screw-conveyer, H, secured upon the shaft A, conveys the feed from the spout through the hollow hub into the reel after forcing it through 65 the wire screen I, which is secured over the discharge opening.

The spout-box G is adjustably secured to the box d by means of bolts m, passing through circular slots n, (seen better in Fig. 8,) so arranged that the spout-box may be adjusted to receive the feeding-spout at any angle that may be most convenient.

The driving-gear is arranged as follows: To the free end of the hub e of the head E is secured a gear-wheel, o, and a pinion, p, is secured to the main shaft A. Upon a counter-shaft, r, below the main shaft are sleeved the gear-wheels q s, the former engaging with the pinion p, and the latter with the gear-wheel o. 75 To each of the gear-wheels q s is secured one member of a clutch, J, and a lever, K, is arranged to open or close the clutch by sliding the gear-wheel q laterally upon its shaft.

A locking device—such as the pin t, engaging into suitable holes—is arranged to lock the lever K into position to hold the clutch J closed or opened, as desired.

L is a sprocket-wheel secured upon the counter-shaft r, and M and N are sprocket-wheels secured upon the ends of the shafts of the conveyers O O, which latter are arranged under the reel in the usual manner. An endless chain, P, passes around the sprocket-wheels and conveys motion to the conveyers. 90

Q is a brush secured at the top of the machine for the purpose of keeping the meshes of the cloth open by being brought in contact therewith when desired.

A system of cut-offs is arranged below the 100 reel in the following manner: At the lower end of the case, where it discharges into the con-

veyer-boxes, a series of slides, R, are arranged along the two sides of the case, cleats *u* being secured to the cant-boards between the slides to hold the latter in position and guide them 5 in opening or closing them. All the slides may be closed or opened independently of each other, so that all or any desired portion of each conveyer may be cut off from access.

The rear head, E, of the reel is provided up- 10 on its inner side with pockets S, into which the tailings are scooped by means of the scoops T, and from which the tailings are discharged through the openings *v* into the discharge-spout U. The scoops T are adjustably se- 15 cured, so that their free ends may be brought nearer to or farther from the periphery of the head. I preferably provide, to this end, the scoops with threaded bolts *w*, which are se- 20 cured to the scoops and project through radial slots *x* in the head. By means of thumb- 25 nuts *z*, secured upon the threaded bolts, the scoops may then be adjusted radially in or out from the outside, an indicator-scale being provided alongside the slots for the proper guidance of the operator.

The case of the machine is of the usual description, but is preferably built in sections, so as to be readily taken apart for the purpose of giving ready access to all the parts to 30 facilitate changes or repairs.

The operation of the machine does not differ from others of its kind; but it presents the following advantages:

First. The adjustable spout-box provides 35 better facilities for connecting it with the feed-spout by allowing it to be directly connected therewith at any angle.

Second. The system of cut-off is simple and perfect, as the material can be cut off 40 from one conveyer to the other at any point desired, the adjustment of the cut-offs being effected instantaneously by raising the hinged cover of the conveyer-box at either side of the machine, and drawing the cut-offs down 45 or pushing them up, as the case may be, suitable catches, *z'*, being secured to each cut-off upon both sides to take hold of. In case of any accident causing a hole in the cloth a cut-off can thus be adjusted at that point, so as to 50 throw the specky flour into the other conveyer without interfering with the good flour on either side.

Third. The outside bolting-cylinder can be stopped at any time without throwing off the 55 belt. Should it become necessary to stop it for the purpose of repairing the cloth, to regulate the discharge of the tailings, or for any other purpose, it is only necessary to throw the clutch out of gear by means of the lever K.

When it is considered that the operation of the machine is thus not materially interfered with, and no general stoppage of other mill machinery need occur on this account, the advantage of this improvement 60 will readily appear.

Fourth. The wire screen in the front head of the reel forms an effective disintegrator, which thoroughly loosens the material to be bolted as it passes into the reel.

Fifth. The device for regulating the discharge of the tailings forms also an important feature, whereby the material can be retained in the reel any length of time found necessary. Its adjustment to any degree of nicety is simple and easily effected while the machine is in 75 operation by first stopping the outside cylinder by means of the lever K, and then raising the sliding panel at the tail end of the machine, which gives access to the regulating devices which adjustably secure the scoops. By 80 loosening the thumb-screws and moving the bolts in the slots provided for them the scoops can be moved from or to the cloth, care being taken to adjust them all alike by means of the index. 85

What I claim as my invention is—

1. In combination with the hollow hub *c* of the reel, the spout-box *G*, communicating therewith, and adjusting devices, as the slot *m* and bolts *n*, for adjusting it radially, substantially as described. 90

2. In combination with the hollow hub *c* of the reel, journaled in the box *d*, the spout-box *G*, communicating with said hollow hub, and adjustably secured to said box, substantially 95 as and for the purposes specified.

3. In a flour-dresser, the combination, with the hollow hub *c* and the force-screw *H*, revolving therein, of the wire screen *I*, secured across the discharge end of said hollow hub, 100 as and for the purposes specified.

4. In a flour-dresser, the combination of the pockets *S*, for the discharge of the tailings, the scoops *T*, and devices for adjusting them from or toward the cloth, substantially as de- 105 scribed.

5. In a flour-dresser, the combination of the head formed with radial slots, the pockets *S*, and the adjustable scoops *T*, all arranged substantially as described. 110

6. In a flour-dresser, the combination of the head formed with radial slots, the pockets *S*, the scoops *T*, the threaded bolts, thumb-nuts, and indicator-scale, all arranged substantially as described. 115

7. In a flour-dresser, the combination of the head *D*, having hollow hub *c*, the head *E*, having discharge-pockets *S* and scoops *T*, the stay-bolts *h*, the clamps *i*, and hoops *j*, the loose straining-ring *k*, straining-screws *l*, and the bolting-cloth secured to the heads *D* *E* and straining-ring *k*, all arranged and constructed substantially as specified. 120
